[57] CLAIM

The ornamental design for a chair, as shown and described.

DESCRIPTION

FIG. 1 is a front-right-top perspective view of a chair, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a front-right-top perspective view of a modified chair embodying my new, original, and ornamental design;

FIG. 9 is a front-right-top perspective view of another modified chair embodying my new, original, and ornamental design; and,

FIG. 10 is a front-right-top perspective view of yet another modified chair embodying my new, original and ornamental design.

The second and third embodiments shown in FIGS. 8 and 9 differ from the first embodiment only in the arrangement of the backrest slats. The fourth embodiment shown in FIG. 10 differs from the first embodiment only in the arrangement of the backrest slats and the absence of support stretchers. It being understood, that all other surfaces of the second, third and fourth embodiments are the same as the first embodiment shown in FIGS. 1 through 7.
